UNITED STATES PATENT OFFICE.

HENRY O. NORVELL, OF MASCOT, TENNESSEE.

FLOTATION APPARATUS.

1,243,093.

Specification of Letters Patent. Patented Oct. 16, 1917.

Application filed July 19, 1916. Serial No. 110,214.

To all whom it may concern:

Be it known that I, HENRY O. NORVELL, a citizen of the United States, residing at Mascot, in the county of Knox and State of Tennessee, have invented a new and useful Improvement in Flotation Apparatus, of which the following is a specification, reference being had to the accompanying drawing.

10 My invention relates to apparatus for effecting the concentration of ore and is intended particularly to accomplish such concentration by the process known as flotation. The object of the invention is to produce an 15 apparatus which is capable of uniform and economical operation and which has large capacity.

In the accompanying drawings,

Figure 1 is a plan of a single unit of my 20 apparatus;

Fig. 2 is an elevation looking at the apparatus from the left, as shown in Fig. 1;

Fig. 3 is an upright section on the line, 3—3, of Fig. 1;

25 Fig. 4 is an upright section on the line, 4—4, of Fig. 1, looking in the direction of the arrow;

Fig. 5 is a detail section on the line, 5—5, of Fig. 4.

30 Fig. 6 is a sectional detail of the gearing shown at the middle of Fig. 2.

The apparatus may comprise a single structure or unit in which the desired operation is exclusively performed; but the apparatus preferably comprises a series of such units in which the material is treated progressively, the material first entering one of the units and portions of the material passing from the first unit into the second unit, 40 where the operation of the first unit is substantially repeated, and so on through the series of such units.

Since these units are substantially duplicates of each other and my invention may 45 be embodied in a single unit, only one unit will be herein described.

Each unit has a tank body comprising a horizontal bottom, A, upright side walls, B, B, and slanting end walls, C; C, rising from 50 the bottom, A, and filling the space between the side walls, B, B, nearly to the upper edges of the latter. The end walls, C, C, slope from their upper ends toward the base or bottom, A, at about the same angle, where-

by said body is made symmetrical relative 55 to an upright line passing through the middle of the bottom, A. The upper edge of each end wall is a little lower than the upper edges of the side walls, B, B.

At the upper portion of the body is a mixing compartment, E. Said compartment is supported by the side walls, B, B, and has a bottom, E¹, and upright walls, E², arranged perpendicular to the side walls, B, B, and having their ends bearing against the inner faces of said walls. The walls, E², extend above the upper edges of the side walls, B, B. An end piece, E³, rests lengthwise upon the upper edge of the right-hand side wall, B, (see Fig. 4) and extends across 70 and is secured to the upper portions of the adjacent ends of the walls, E². By means of this end piece, E³, the walls, E², and the bottom, E¹, are supported. Said bottom and said walls may also be secured to said side 75 walls, B, B, by nailing or otherwise.

At the opposite side wall, B, an end piece, E⁴, is seated against said wall and between the side walls, E², and the bottom, E¹, of the mixing compartment, said end piece, E⁴, extending above the upper edge of the wall, B, as shown by Fig. 4. The outer face of said end piece, E⁴, and the corresponding end of the bottom, E¹, have an upright groove, e⁴, to receive the stem, B³, described 85 later on. This end of the mixing compartment may be secured in any desired manner as by nails driven through the wall, B, into the end piece, E⁴, or the bottom, E¹, or the walls, E², or all of these members. 90

In the lower portions of each of the walls, E², is a port E⁵. In one of the end pieces, E³, is a port, E⁶. In the opposite wall, B, near the bottom or base, A, is a port, A¹, to which is applied a gate valve, A², which is 95 movable up and down between upright guide strips, B¹. The upper end of said gate has two upright ears, B², between which rests the lower end of a stem, B³. A pintle, B⁴, extends horizontally through said ears and 100 the lower end of said stem to secure the latter to said gate. Said stem extends upward along the inner face of said wall, B, and slidably through the groove, e⁴, at the left-hand end of the compartment, E. An addition, B⁵, is applied to the outer face of the upright wall, B, opposite said stem, with its upper edge even with the upper edge of the 105

wall, B. The upper edge of said wall and of said addition make a horizontal seat for a base, B⁶, in which is journaled an upright nut, B⁷, on the upper portion of which is a 5 bevel gear, B⁸. Above the wall, B, the stem, B⁸, is bent horizontally and then upward through said nut. (See Figs. 2, 4 and 6.) This last upright portion of said stem is screw threaded to fit the threads of the nut, so that the turning of said nut will raise or lower said stem, and the raising or lowering of the stem will raise or lower the gate, A². A bevel gear wheel, B⁹, meshes with the bevel gear wheel, B⁸, and is mounted on a 15 horizontal shaft, B¹⁰, which rests in bearings, in the base, B⁶, and has on its outer end a hand wheel, B¹², by means of which said shaft and the bevel gear wheel, B⁹, may be turned in either direction for raising or lowering said gate to vary or cut-off the flow 20 through the port A¹.

In the mixing compartment, E, is an agitator, F, supported by the lower end of an upright shaft, F¹, which is supported in 25 fixed bearings, F², and supports at its upper end a pulley or similar wheel, F³, to which power is applied for the rotation of said shaft and said agitator. At the outer side of each end wall, C, is a receiving 30 trough, D, in position to receive flow of material from the interior of the body of the machine over the upper edge of the adjacent end wall, C.

Adjacent each trough, D, is a skimmer, 35 the function of which is to facilitate the flow of material from the interior of the body into the adjacent trough. Each of said skimmers comprises a horizontal shaft, G, resting in bearings, G¹, seated on the 40 upper edges of the side walls, B. Adjacent the inner face of each wall, B, the shaft, G, has a rigid cross arm, G². Said cross arms and said shaft are cut by a common plane. Two gravity blades, G³, are arranged 45 parallel to said shaft and between said cross arms and are suspended from said cross arms by lugs, G⁴, formed on the upper corners of said blades and extending loosely into said cross arms. One end of 50 each of said shafts extends through one of the bearings, G¹, and supports a pulley, G⁵, to which power is to be applied for rotating its shaft in the proper direction to cause the blades, G³, to move upward between said shaft and the adjacent wall, C.

A pipe or similar conducting member, E¹², is placed for the delivery of material into the mixing compartment, E. The drawings show said conducting member extending into the port, E⁶, of the end piece, E³, of the mixing compartment.

From the port or outlet, A¹, which is controlled by the gate, A², as already described, a pipe, A³, leads obliquely upward 65 into the mixing compartment of the next

unit, if another unit is used. If not, said pipe is to discharge elsewhere.

A pipe, A⁴, extends upward through the base or bottom, A. Said pipe leads from a source of water supply under pressure and 70 has a cut-off valve, A⁵, which is normally closed. On the lower portion of each wall, C, is a faucet, C¹, through which the interior of the structure may be drained when desired. 75

While the agitator, F, and the skimmers are in motion, the pulp is delivered into the mixing chamber, as above described, and a suitable quantity of oil is delivered into the mixing chamber. The agitator causes the thorough mixing of the oil with the pulp before the latter passes out of the mixing chamber through the ports, E⁵. The foam or froth forming on the surface is gradually moved outward by the skimmers into the 85 troughs, D, D. The heavier portions of the pulp gradually flow outward through the port, A¹. This flow is varied by means of the gate, A²; and varying such flow in- 90 versely varies the flow into the trough. 90

When there is an abnormal accumulation of solid comminuted material in the lower portion of the compartment, water is forced upward through the pipe, A⁴, by opening the cut-off valve, A⁵. When there is occasion for entirely emptying the compartment, the faucets, C¹, are opened. 95

It is to be noted that the agitator is an aerating agitator; and that there is elongation of the tank between the agitator discharge and the froth overflows; and that there are extension and non-obstruction of the interior space of the tank below the agitator, these prolongations being in the lines of feed to permit dropping of gangue 105 from the froth and surface flow, and the meeting of oppositely flowing eddies at the middle of the apparatus below the agitator being given upward deflection and partial neutralization which promotes settlement of 110 gangue, the consequence of which will be evident when it is considered that ore subjected to froth separation is usually more or less slimy.

I claim as my invention,

1. In combination, an elongated tank having froth overflows at opposite ends, an aerating agitator, having a discharging portion depending slightly below the liquid level in the tank and having outlets adapted to discharge strata of aerated pulp in the directions of the froth overflows, the tank being substantially unobstructed below the agitator and having a settling space below the same extending throughout the length 120 of the tank, substantially as described.

2. In combination, an elongated tank having froth overflows at opposite ends, an aerating agitator, having a discharging portion depending slightly below the liquid 125

level in the tank and having outlets adapted to discharge strata of aerated pulp in the directions of the froth overflows, the tank being substantially unobstructed below the 5 agitator and having a settling space below the same extending throughout the length of the tank, and means for driving froth

toward said overflows, substantially as described.

In testimony whereof I have signed my 10 name, in presence of two witnesses, this 3rd day of July, in the year one thousand nine hundred and sixteen.

HENRY O. NORVELL.
